UNITED STATES PATENT OFFICE.

FRED W. MALEY, OF BAKERSFIELD, CALIFORNIA.

ABSORBENT COMB.

1,147,681.

Specification of Letters Patent. Patented July 20, 1915.

Application filed June 3, 1913. Serial No. 771,460.

To all whom it may concern:

Be it known that I, FRED W. MALEY, a citizen of the United States, residing at Bakersfield, in the county of Kern and State 5 of California, have invented new and useful Improvements in Absorbent Combs, of which the following is a specification.

The present invention relates to absorbent combs for use in cleaning and drying the 10 hair, and has for its primary object to provide an improved device of this character consisting essentially in a suitable frame for mounting absorbent material in such position as to engage the hair of the user between the opposing surfaces of such material 15 to absorb the moisture and surplus oil in the hair.

A further object is to provide the absorbent material in such a form that the oppositely disposed portions thereof will form 20 miniature combs which are adapted to operate upon each of the hairs individually for scraping off the dandruff, and small particles of lint and other foreign matter. In 25 the exemplification shown in the drawing, this purpose is carried out with plush having blank spaces formed in the web for receiving the foreign matter referred to.

Other and further objects will appear in 30 the specification and be carefully pointed out in the appended claims.

In the drawing, Figure 1 is a side elevation of my improved absorbent comb. Fig. 2 is a bottom plan view. Fig. 3 is a longitudinal sectional view approximately upon the line 3-3 of Fig. 2. Fig. 4 is a transverse sectional view approximately upon the line 4-4 of Fig. 3. Fig. 5 is a detail perspective view of the frame and handle, the 35 teeth being removed. Fig. 6 is a perspective view of one of the plush stretching members showing the ribs. Fig. 7 is a perspective view of the locking cap for the frame.

Referring now to the drawings in detail, 40 the numeral 1 designates the frame, or back of the comb which is preferably of a substantially rectangular formation, and which has connected therewith a rearward, longitudinally extending handle 2. The upper 45 and rear portion of the frame, at its junction with the handle 2, is formed upon each of its sides with a lip 3, the longitudinal edges of which are in a plane with the longitudinal sides of the frame. The sides of the

frame are spaced a suitable distance away 55 from each other, and each of the said sides has its inner face provided with a plurality of recesses 4, thus forming the projecting portions 4', the recesses upon one of the sides of the frame being disposed diametrically 60 opposite the recesses upon the other side of the frame. The recesses have their inner walls straight, while the side walls provided by the said recesses preferably converge inwardly from the top toward the bottom of 65 the frame, and the lower portion of the frame is provided with a plurality of bars which connect the opposite sides of the said frame, and which have their longitudinal edges arranged in a plane with the lower 70 walls provided by the recesses.

The numeral 7 designates the plush stretching members or plates. Each of these members is constructed from rubber or gutta-percha and has its side edges provided 75 with ribs 8. The ribs are of a greater thickness than the thickness of the plates and extend transversely on each side of the plate and extend a suitable distance below the lower edge of the plate. The opposite side 80 faces of each of the ribs have their upper portions flared outwardly to provide substantially wedge-shaped members which are adapted to frictionally engage with the side walls provided by the recesses 4 when the 85 plates are arranged upon the comb.

The absorbent material employed with the comb, preferably comprises a strip of plush 9, the same being provided with longitudinally extending spaced blank spaces which 90 are formed in the web of the strip. The strip is of a width approximately equaling or slightly less than the width of the stretching members or plates between the inner edges of the ribs 8.

The plush is applied by arranging the same over the top of the frame between its connecting rods, and the plate or stretching member is brought into engagement with the plush and passed through the registering depressions adjacent the outer end of the frame. The remaining plates or stretcher members in a like manner are passed through the succeeding depressions to fold the plush so that the same is arranged over the connecting bars, and between the opposite faces of the plates or stretcher members.

As thus described, it will be noted that the

plush is arranged directly behind the ribs, and that the faces of the strips of plush between the spaces provided by the web thereof are disposed directly opposite each other, and provide miniature combs which are adapted to operate upon each of the hairs individually to remove surplus oil and foreign matters therefrom as well as to effectually dry the hair. The action of the plush is facilitated by the ribs 8, which open furrows or paths through the hair to divide the hair into finer bodies to be acted upon by the plush.

In order to sustain the plates and ribs in proper position upon the frame, as well as for retaining the free ends of the plush strip, I have provided the frame with a removable cap or closure 9'. The cap is provided with opposite longitudinal flanges and 20 with a connecting end flange. The longitudinal flanges are spaced to snugly engage with the outer faces of the sides of the frame, while the end flange is provided with inturned cleats 10 which also connect with the lower edges of the side flanges. Centrally connected with the inner face of the end flange and having its opposite ends arranged beneath the cleats is a spring plate 11. The transverse end of the cap opposite 30 to that provided with the flange is formed, adjacent the side flanges with inturned catch members 12, which are adapted to engage with the lips 3 of the frame, when the cap is positioned upon the frame. The spring 11 comprises a curved member, and it will be noted that when the cap is slid over the frame the ends of the spring are compressed to permit of the catch members 12 passing the lips 3, and also arranging the plates 40 10 below the under face of the frame. When a pressure upon the plate is released the catch members 12 will, through the medium of the spring 11, be automatically brought into engagement with the lips 3, and the cleats 10 are of sufficient length to retain their engagement with the frame 45 after the spring has been expanded.

From the above description, taken in connection with the accompanying drawings, 50 the simplicity, as well as the advantages of the device, and the operation of the same, will, it is thought be apparent to those skilled in the art to which such devices pertain. It will be noted that the absorbent strip is comparatively wide so that a great number of hairs will be engaged thereby before both of the teeth of each of the plates pass through the hair, and also that owing to the peculiar construction of the 55 plates and ribs, the absorbent material will, through the medium of the teeth, be sustained against lateral displacement, while the said plates effectively serve as stretching and binding elements for retaining the plush

in a taut condition, and immediately to the rear of the ribs.

Having thus described the invention, what I claim is:—

1. In an absorbent comb, a frame provided with a plurality of removable plates 70 arranged in said frame, said plates having their opposite edges provided with ribs and said plates being adapted to engage with and stretch an absorbent material to cause the same to lie flatly against the opposite 75 faces of the plates and directly behind the ribs.

2. In an absorbent comb, a frame having side members, said members provided with spaced recesses upon their inner faces, plates 80 having their edges formed with ribs arranged within the recesses and extending beyond the frame, the said plates adapted to stretch an absorbent material to retain the same back of the ribs and against the 85 opposite faces of the plates.

3. In an absorbent comb, a frame having side members, said members provided with substantially V-shaped recesses upon their inner faces, plates having their opposite 90 edges formed with ribs which extend beyond the lower edge of each of the plates, the opposite faces of the ribs at their upper ends being wedge shaped to engage within the V-shaped recesses of the frame, the said 95 plates being adapted to engage with and stretch an absorbent material to retain the same back of the ribs and against the opposite faces of the plates.

4. In an absorbent comb, a frame having 100 relatively spaced side members provided with recesses disposed diametrically opposite each other, the lower portion of said frame being provided with a plurality of 105 relatively spaced bars, said bars being arranged in the same plane as the projecting portions of the side of the frame and stretching plates arranged within the recesses adapted to stretch an absorbent material and retain the same against the opposite faces 110 of the plates.

5. In an absorbent comb, a frame provided with a series of recesses adapted to receive plush stretching plates, said plates being arranged in said recesses and extending beyond the frame, the said plates adapted to stretch an absorbent material between its ends, the free ends of said absorbent material being held in position by a cap which is adapted to engage the free ends of the 115 120 absorbent material and to hold said stretching plates in applied position.

6. In an absorbent comb, a frame provided with a series of recesses adapted to receive plush stretching plates, plush stretching plates arranged in said recesses and extending beyond the frame, each of the said plates adapted to stretch an absorbent ma-

terial between its ends, a removable cap adapted to be placed over the top of the frame and down the sides of the frame to hold said plates in applied position, to engage the free ends of said absorbent material to hold them in a taut position, and to provide a cover for the frame.

Copies of this patent may be obtained for five cents each, by addressing the "Commissioner of Patents, Washington, D. C."

In testimony whereof I affix my signature in presence of two witnesses.

FRED W. MALEY.
